AUTOMATIC DOOR OPENER

Filed Oct. 10, 1930

Byron B. Ashbrook

INVENTOR

Victor J. Evans

ATTORNEY

UNITED STATES PATENT OFFICE

BYRON B. ASH BROOK, OF JOHNSTOWN, OHIO

AUTOMATIC DOOR OPENER

Application filed October 10, 1930. Serial No. 487,858.

This invention relates to improvements in automatic door openers and has for the primary object, the provision of a device of the above stated character, whereby the door or doors to which the device is applied will be automatically released from a latched position and swung to an open position when the device is subjected to an impact, thus providing a device especially adaptable for garages or for garage doors or the like where the driver of an automobile may subject the device to an impact by driving the automobile thereagainst to release the doors that they may swing to an open position when the automobile is backed or reversed out of the path of the doors, thereby obviating the driver manually opening the doors or having to leave the seat of the automobile in order to release and open the doors.

Another object of this invention is the provision of an automatic door opener of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be herein-after more fully described and claimed.

For a complete understanding of my invention, reference is to be had to the following description and accompanying drawing, in which:

Figure 1 is a fragmentary rear elevation illustrating doors of a building or garage with an automatic door opener applied thereto and constructed in accordance with my invention.

Figure 2 is a sectional view taken on the line 2—2 of Figure 1.

Figure 3 is a fragmentary sectional view illustrating the latch.

Figure 4 is a similar view illustrating the operating means for the latch.

Figure 5 is an elevational view illustrating a combined operating and locking means for the latch.

Referring in detail to the drawing, the

numeral 1 indicates a fragmentary portion of a building which may be a garage or the like and the door way thereof is closed by hinged doors 2, one of which is provided with a overlapping strip 3 to retain the other door in a closed position when the former door is fastened. The doors 2 are mounted on hinges 4 which are secured to the building 1 so that the doors may swing outwardly of the building. Brackets 5 are secured to the building 1 and carry expansion springs 6 engaging the doors 2 for urging the doors into an open position when released from a closed position by the latch which will be hereinafter more fully described.

A keeper 7 is carried by the building 1 and slidably receives a latch bolt 8 having a beveled end 9 and which is slidably mounted in a casing 10 secured to one of the doors. The latch bolt 8 is provided with a bore 11 to slidably receive the upper end of an operating rod 12 and which is provided with a head 13 engaging a spring 14 located within the bore 11 for the purpose of yieldably supporting the latch bolt 8 relative to the rod 12 and further providing a construction which will disengage the latch from the keeper 7 during a downward movement of the operating rod 12.

A bracket 15 is secured to the door on which the casing 10 is mounted and includes inner and outer plates 16 and 17 respectively and on which are formed relatively spaced ears 18 and 19. The plates 16 and 17 are provided with aligned openings 19' in registration with an opening 20 extending through the respective door. A pivot pin 21 connects the ears 18 and has journaled thereon a combined operating and locking lever 22 of arcuate shape and which is provided at one end with an eye to receive a ring 23 carried by the lower end of the operating rod 12 to provide a flexible connection between said lever and the rod. The opposite end of the lever 22 is provided with a slot 24 to receive the arm portion 25 of a substantially L-shaped lever 26. The arm portion 25 of the lever 26 besides extending through the slot 24 extends through the

opening 19' of the plates 16 and 17 and the opening 20 of the respective door so as to position the arm portion 27 of the lever 26 at an opposite side of the respective door 5 from that of the lever 22 and on the outside of the door to be given an impact for the purpose of releasing the latch bolt 8 from the keeper 7. The arm portion 27 of the lever 26 inclines outwardly and downwardly from the outer face of the door and a shoulder 28 is formed on the arm portion 25 adjacent to the arm portion 27 to form a seat to receive a rib 29 on the plate 17 of the bracket 15 to pivotally mount the lever 15 26 to the door. The arm portion 27 of the lever 26 when being moved towards the door will cause the lever 22 to be rocked upon its pivot disengaging the catch 8 from the keeper 7 freeing the doors that they may swing 20 automatically to an open position by the influence of the springs 6.

The journal portion of the lever 22 and at one side of the lever is provided with teeth 30 to engage corresponding teeth on 25 a member 31 secured to one of the ears 18 of the bracket 15 for the purpose of holding the lever 22 in a position retracting the latch bolt 8 from the keeper 7 consequently after the lever 26 has been once actuated, 30 by an impact, the lever 22 is moved into a position to release the catch from the keeper and is locked in this position by the teeth 30 engaging the teeth on the member 31 therefore it will be seen that the doors are 35 then free to swing open by the influence of the springs 6.

In operation, the doors occupy a closed position, the driver of an automobile causes the bumper or some other part of the automobile to strike against the arm portion 27 40 of the lever 26 imparting a movement to the lever 22 which retracts the latch from the keeper 7 and holds said latch in a retracted position. The driver then reverses the direction of the automobile and the doors 45 swing to an open position under the influence of the springs 6 leaving the door way of the garage or building fully open that the driver of the automobile then can proceed with the automobile into the building 50 or garage.

The ears 19 of the bracket 15 are provided with aligned openings 32 to receive a pad-lock or the like for the purpose of holding 55 the lever 26 against pivotal movement consequently preventing the unlocking of the doors.

If desired an expansion spring 33 may be located in the casing 10 for normally urging 60 the latch bolt 8 outwardly, however it will be understood that the latch bolt is limited in its outward movement by the operating rod 12, and the latter is provided with a turn-buckle 35 to permit the length thereof 65 to be varied. A spring 34 is located on the

pivot pin of the lever 22 and bears against the latter and one of the ears 19 of the bracket 15 to yieldably support the lever on the pivot pin and to normally urge the lever in a direction that the teeth thereof will contact with the teeth on the bracket 15 when the lever assumes a position to retract the catch from the keeper.

While I have shown and described the preferred embodiment of my invention, it will be understood that minor changes in construction, combination and arrangement of parts may be made without departing from the spirit and scope of the invention as claimed.

Having thus described the invention what is claimed is:

A latch operating device comprising plates secured to opposite faces of a door and having aligned openings, spaced ears on one of said plates, a rib formed on the other plate, an L-shaped lever having a recess receiving the rib with a portion thereof extending through the openings and the door, a pivot pin connecting said ears, teeth on one of said ears, an arcuately curved lever journalled and slid able on the pin and having one end connected to a latch operating medium and provided in its opposite end with a slot to receive the first named lever, teeth on the second lever, and tension means on the pin to urge the second lever into a position to engage the teeth and cause a securing of the second lever against movement in one direction after being moved by the first lever.

In testimony whereof I affix my signature.
BYRON B. ASHBROOK.
